WILLIAM L. ROBEDEE, OF ELBRIDGE, NEW YORK, ASSIGNOR OF ONE-HALF TO RAY M. CORNWELL, OF SYRACUSE, NEW YORK.

GUN-BARREL FOR SHOTGUNS.

No. 833,484.

Specification of Letters Patent.

Patented Oct. 16, 1906.

Application filed September 12, 1905. Serial No. 278,104.

To all whom it may concern:

Be it known that I, WILLIAM L. ROBEDEE, of Elbridge, in the county of Onondaga, in the State of New York, have invented new and useful Improvements in Gun-Barrels for Shotguns, of which the following, taken in connection with the accompanying drawings, is a full, clear, and exact description.

This invention relates to certain improvements in gun-barrels for shotguns, in which the barrel is provided with a continuous series of taper bores progressively but smoothly merging one into the other at gradually (though slightly) increasing angles with the axis of the barrel, thereby constituting what may be termed a "series" choke bore as distinguished from a continuous single taper or choke, for the purpose of concentrating the charge at the target within a smaller area than has heretofore been practiced.

I am aware that it is common to reduce or choke the bore at the muzzle; but I believe that I am the first to provide a barrel with a series-choke bore produced by a series of tapers all converging toward the muzzle at progressively-increasing angles with the axis.

In several comparative tests with my series-choke barrel and the ordinary single-choke barrel I find that with my barrel an average of more than ninety per cent. of the charge is concentrated within a circular target area of thirty inches diameter at forty yards distance as against seventy-five per cent. with an ordinary single-choke-bore gun of the same dimensions but single choke and under the same distance and target conditions. This enables the user of my improved barrel to not only concentrate a greater percentage of the full charge within a smaller target area than is practicable with a single-choke barrel, but also proportionately increases the carrying distance of the effective charge, the advantages of which are clearly manifest.

In the drawings, Figure 1 is a longitudinal sectional view of a portion of a gun-barrel embodying the features of my invention. Fig. 2 is a transverse sectional view taken on line 2 2, Fig. 1.

In order that my invention may be clearly understood, I have shown about eight inches of the muzzle end of my improved barrel A as provided with a series of tapers *a b c*, which begin about six inches back of the muzzle of

the barrel and merge smoothly one into the other, so that all of the tapers converge toward the muzzle at progressively-increasing angles with the axis of the barrel. These tapers are considerably exaggerated in the drawings for the purpose of more clearly bringing out this feature of my invention and it will be seen that each taper is of substantially the same length, the larger end of the first taper *a* being of the same diameter as that of the rest of the main portion of the bore toward the breech of the barrel, and the larger end of the taper *b* is identical in diameter with that of the smaller end of the taper *a*, while the larger end of the taper *c* is of the same diameter as that of the smaller end of the taper *b*, so that these several tapers *a*, *b*, and *c* gradually diminish toward the muzzle of the barrel, but at increasing angles with the axis of the said barrel, for the purpose of gradually compressing and at the same time slightly elongating the charge in its transition to and discharge from the muzzle of the barrel, in which condition it is carried a considerable distance without spreading, and, in fact, in the tests which I have made I find that at a distance of forty yards fully ninety per cent. of the charge is concentrated within target area having a diameter of less than thirty inches, while with an ordinary "single choke" under the same conditions I have been unable to concentrate more than seventy-five per cent. within the same target area. This shows conclusively that with my improved series-choke barrel I am enabled not only to concentrate a larger percentage (nearly all) of the charge within a comparatively small area at a given distance, but I am also enabled to carry the charge in a more concentrated condition a greater distance than with a single choke such as is now in common use.

I have shown each taper as being about two inches in length simply because the gun barrel in which my experiments were made was bored in this manner; but I may find upon further experiment that a greater or less length of taper may be equally serviceable or superior in carrying out the objects of my invention. Therefore I do not wish to limit myself to the exact portion of the barrel in which these series tapers are bored further than that they must merge one into the other at progressively-increasing angles with

the axis of the barrel, thereby producing what may be termed a "continuous" series-choke bore.

What I claim is—

5. A gun-barrel having a series-choke bore formed by a series of tapered bore-sections each of substantially the same length, the taper of the bore-section forming the muzzle of the barrel being greater than the taper of the bore-section adjacent the breech of the bar-

rel, and the taper of the bore-section interposed between said other two bore-section being of less taper than the bore-section adjacent the breech.

In witness whereof I have hereunto set my hand this 8th day of September, 1905.

WILLIAM L. ROBEDEE.
